CONNECTION FOR TELEPRINTERS

Ehrhard Rossberg, Berlin-Siemensstadt, Germany; vested in the Alien Property Custodian

Application September 20, 1940, Serial No. 357,533
In Germany September 25, 1939

10 Claims. (Cl. 178—2)

This invention relates to a connection for teleprinters in which a transmitter is combined with a number of receivers, preferably with two receivers.

My invention contemplates the provision of an improved arrangement whereby the shaft of each receiver is blocked by a pawl, whose release is effected in accordance with the reception of the call signal.

The pawl is preferably actuated by means of a magnet which operates in response to the reception of the call signal. If call signals which have a given minimum duration are utilized a known combination consisting of a condenser and a resistor is preferably employed. The locking magnets may be provided with holding windings so that they remain energized during operation.

Further details of the invention will be apparent from the following description taken in connection with the accompanying drawings, in which

Fig. 1 shows the arrangement of the pawls and magnets;

Fig. 2 is a diagrammatic circuit drawing showing the essential parts of the system; and

Fig. 3 is a similar drawing showing somewhat simplified circuits.

In the state of rest the magnets $Sp1$ and $Sp2$ and the signal lamps $KL1$ and $KL2$ are deenergized. Each magnet prevents its associated receiver shaft from rotating even when the receiver magnet receives the starting impulse. Only upon the energization of the magnet $Sp1$ or $Sp2$ is the corresponding receiver shaft permitted to rotate by withdrawal of the pawls $K1$, or $K12$, respectively, in order to translate the signals received.

In Fig. 2 is shown the switching system for the operation of the apparatus. If, for instance, a call is received over the line $L1$, the calling relay $AR1$ is released in accordance with the calling impulse which consists in an interruption of current. The contact $ar1$ is released to the position shown so that the condenser $C1$ discharges through the resistance $R1$. As soon as the starting impulse ceases, the current flows through the line $L1$ so that the armature of the relay $AR1$ is again attracted. The condenser $C1$ is charged over a circuit through the winding I of the magnet $Sp1$, which circuit is as follows: earth, condenser $C1$, contact $ar1$, magnet $Sp1$, battery, earth. The locking magnet attracts its armature so that the shaft $EW1$ (Fig. 1) may begin to rotate and the contact $sp1a$ is closed. In this man-

ner a holding circuit is established through the winding II of the magnet $Sp1$, extending from earth, by way of contact $sp1a$, magnet $Sp1II$, quenching key $LT1$, and battery to earth. The signal lamp $KL1$, which indicates that the receiver with the magnet $EM1$ (Fig. 2) and the shaft $EW1$ (Fig. 1) is in operation over the line $L1$, is inserted in the circuit in parallel relation to the circuit just traced. Upon the operation of the magnet $Sp1$ the motor M is connected to the current supply circuit N through the contact $sp1b$. The receiving magnet $EM1$ can now receive the signals incoming over the line $L1$. The transmitting contact sk is arranged in the circuit in accordance with the position of the double-throw switch $U1$. Over the line $L1$ a two-way working may therefore be effected with the aid of the receiving magnet $EM1$ and the transmitting contact sk . Over the line $L2$, however, only reception may be effected at this time, in view of the position of the change-over switch $U2$.

A call arriving over the line $L2$ acts in a corresponding manner through the relays $AR2$ and the locking magnet $Sp2$. If two-way working is to be effected the directional switches $U1$ and $U2$, which may under certain circumstances be combined in one switch, must be switched over in a corresponding manner. A call over the line $L1$ or $L2$ extending to the remote station takes place after changing over the directional switch to the corresponding position by depressing the key RT . The closed circuit current is thus interrupted in the line, the remote apparatus is started in the manner as described above and also the relay $AR1$ or $AR2$ is released at the home station so that the apparatus is allowed to run down.

If the resistance $R1$ is not of the same magnitude in the calling and called apparatus it may occur that the home apparatus starts, but the remote apparatus does not start at the remote station, because the calling impulse was too short. For this reason auxiliary resistors $R2$ are in addition provided which are short-circuited through the contacts $RT1$ and $RT2$ of the calling key. If the calling key is therefore depressed the time constant of the circuit $C1$, $R1$ is increased by the resistances $R2$ so that the calling impulse must be transmitted somewhat longer in order to start the home apparatus, thus ensuring a starting of the remote apparatus.

In Fig. 3 the connection as shown in Fig. 2 is simplified. In this case only one calling relay AR is provided which, however, carries two windings. Besides only one combination consisting of a

condenser and a resistor is provided. The relay AR is so wound that it is already released in the state of rest when current flows over the lines L1 and L2 in the opposite direction in the two windings. However, during the operation the armature of the relay is attracted in response to the relatively short telegraphic impulses. The operation is effected in the same manner as in Fig. 2. The relay AR is actuated in response to a call, for instance, through the winding II in the event of the line L1 being deenergized. In this manner the condenser C1 is discharged through the resistance W in order to transmit at the end of the starting impulse upon the release of the relay AR an impulse through the magnet FM1, winding I and the directional switch U1a. The locking magnet FM1 is attracted and remains energized through its contact fm1a. The motor M is started through the contact fm1b. Otherwise the operation is effected in the same manner as in Fig. 2.

The connection may be simplified to a further extent if a make and break contact is allotted to the receiving magnet EM1 or EM2 shown in Fig. 2 or 3. This magnet has then the same function as the contacts ar1 and ar2 (Fig. 2) or ar (Fig. 3).

What is claimed is:

1. In a printing telegraph system, a transmitter, two receivers, said transmitter and receivers being located at the same station, two lines incoming to said station and terminating in said receivers, respectively, circuit connections over which one line circuit is completed by way of its associated receiver and the said transmitter in series, the other line circuit being completed by way of its associated receiver alone, and switching means for altering said circuit connections to include said transmitter in the second line circuit but not in the first.

2. In a printing telegraph system, two line circuits incoming to a telegraph station, two receivers at said station connected in said line circuits, respectively, a transmitter at said station common to said line circuits, a connection from one line circuit extending through the associated receiver to said transmitter, a connection from the second line circuit extending through the associated receiver to a source of current and excluding said transmitter, and a switching device for reversing said connections.

3. In a printing telegraph system, a line circuit adapted for two-way operation and including a receiver and a transmitter at the same end of the line, a second line circuit adapted for one-way operation only and including a receiver, and a switching device for shifting the transmitter from the first line circuit to the second, whereby

the second line circuit is converted to two-way operation and the first line circuit is converted to one-way operation.

4. In a printing telegraph system, a receiver having a rotatable shaft, a pawl normally preventing rotation of said shaft, a magnet for withdrawing said pawl to start the receiver, a relay in said receiver responsive to an incoming call signal, a condenser, and a circuit for said magnet including said condenser and controlled by said relay.

5. In a printing telegraph system, a receiver having a rotatable shaft, a pawl normally preventing rotation of said shaft, a magnet for withdrawing said pawl to start the receiver, a relay in said receiver responsive to an incoming call signal, a condenser, and a circuit controlled by said relay for charging said condenser in series with said magnet to energize the magnet.

6. A system as claimed in claim 5, wherein a locking circuit is provided for maintaining the magnet energized after the condenser has become charged.

7. In a printing telegraph system, a receiver having a shaft, a pawl normally preventing rotation of said shaft, a magnet for withdrawing said pawl to start the receiver, a relay in said receiver deenergized at the beginning of a call signal and energized at the end of such signal, a condenser, a circuit completed by the deenergization of said relay for discharging said condenser at a predetermined rate, and a circuit completed by the energization of said relay for charging said condenser in series with said magnet to energize the same.

8. A printing telegraph system as set forth in claim 7, arranged for two-way transmission with receivers at opposite ends of a line circuit, said system being provided with signal transmitters associated with the respective receivers, and means in each transmitter responsive to the operation thereof for automatically decreasing the discharge rate of the condenser in the receiver at the same end of the line.

9. In a printing telegraph system, two receivers each having a shaft which is normally prevented from rotation, magnets in said receivers for releasing said shafts, lines incoming to said receivers, respectively, a differential relay having two windings included in said lines, respectively, and circuit connections over which said magnets are controlled by said relay.

10. A printing telegraph system as set forth in claim 9, wherein a manual switch is provided to operatively associate the differential relay with either release magnet at will.

EHRHARD ROSSBERG.
